Specification of Letters Patent.

Patented Feb. 5, 1918.

Original application filed January 27, 1913, Serial No. 744,465. Divided and this application filed January 3, 1916. Serial No. 69,984.

To all whom it may concern:

Be it known that I, FRED ASHWORTH, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

This invention relates to shoe sewing machines, and more particularly to shoe sewing machines of the type comprising a straight hook needle and devices coöperating therewith to form a chain stitch seam in which the shoe is supported during the sewing operation by a rotatable horn extending within the shoe. Such shoe sewing machines are generally known in the art as machines of the McKay type.

In shoe sewing machines of the McKay type, at present in common commercial use, the feed mechanism is so constructed and operated as to cause a great deal of noise and vibration during its operation, and for this reason, has tended to limit the speed at which such machines could be run.

The primary object of the invention is to provide shoe sewing machines of the McKay type with an improved feed mechanism constructed and arranged to feed the work in a uniformly reliable manner which is especially adapted for use in a high speed machine.

With the above object in view, the invention consists in the novel and improved constructions, arrangements and combinations of parts hereinafter described and particularly pointed out in the claims, the advantages of which will be obvious to those skilled in the art.

In the accompanying drawings illustrating the preferred form of the invention, Figure 1 is a view in side elevation of the head of a machine embodying the invention; Fig. 2 is a view in front elevation of the head of the machine; Fig. 3 is a sectional elevation taken substantially on the line 3—3 of Fig. 1; Fig. 4 is an enlarged view in front elevation of the head of the machine, illustrating the needle in its lower

most position; and Fig. 5 is a view similar to Fig. 4 showing the needle in raised position.

Referring to the drawings, the work supporting horn is indicated at 2 and the presser foot coöperating therewith at 4. In the present embodiment of the invention the horn is vertically immovable and the presser foot is mounted for vertical movement to accommodate work of varying thicknesses. The presser foot is secured to the lower end of a presser bar 6 which is arranged to slide vertically in a suitable guide formed in the lower plate 8 of the frame of the machine. A cap or sleeve 10 arranged to slide in a guide in the upper plate 12 of the frame is secured to the upper end of the presser bar, and the upper end of the cap is engaged by a coiled spring 14 which acts yieldingly to hold the presser foot in engagement with the work. The downward movement of the presser foot, when no work is in the machine, is limited by the engagement of the lower end of the sleeve 10 with the bracket 16 provided with an opening through which the presser bar passes, and adjustably secured by screws 18 to the side of the machine frame.

During each cycle of operations of the machine the presser foot is lifted from the work a substantially uniform distance to permit the work to be fed between the presser foot and the horn, and after the work has been advanced a distance equal to the length of one stitch the presser foot is yieldingly depressed into engagement with the work, accommodating itself to the thickness of the work. The mechanism for actuating the presser foot in this manner during the operation of the machine, and the mechanism for lifting the presser foot manually to permit the removal and insertion of work, are fully described in applicant's pending application Serial No. 744,465, filed January 27, 1913, and therefore need not be described in the present application.

In the machine illustrated in the drawings, the work is fed by means of an awl or feed point 20 mounted in the lower end of an awl bar 22 pivoted at 24 on an extension of the sleeve 10, so that the vertical position of the awl bar is varied as the position of

the presser foot is varied in accordance with the thickness of the work. The work is fed by the lateral swinging movement of the awl bar on its pivot while the awl is projected 5 into engagement with the work. The mechanism for imparting the lateral feed movement to the awl bar comprises a link 26 pivotally connected at one end to the awl bar and at the other to an arm 28 fixed to a 10 rock shaft 30. A second arm 32 is secured to the rock shaft 30 and is connected by means of a link 34 to a lever 36 pivoted at 38 on the machine frame, and provided with a cam roll 40 which engages a cam groove 15 42 in the cam disk 44 fixed to the main shaft 46 of the machine. A bolt and slot connection is provided between the arm 32 and the link 34, so that the length of feed may be varied, the slot being made in the form of 20 an arc which is struck from the center of the connection between the link 34 and the lever 36 when the parts of the feed mechanism are in the positions which they occupy at the beginning of a work feeding stroke. 25 With this construction, the adjustment of the bolt in the slot in the lever 32 will produce variations in the length of feed, while the feeding devices will always start from the same position at the beginning of their 30 work feeding movement, regardless of the length of the feed.

The feed point or awl is mounted in the awl bar so that it can be projected into engagement with the work and held in engagement therewith as the awl bar is swung forward to feed the work, and so that it can be retracted out of engagement with the work during the movement of the awl bar back to starting position. In the construction illustrated the awl is provided with a shank which is arranged to slide in a suitable guide in the lower end of the awl bar, and rack teeth 48 are formed on the shank of the awl which are engaged by the teeth 45 of a pinion 50 journaled on a shaft 52 mounted in the awl bar. A rack bar 54 is mounted to slide vertically in the lower end of the awl bar, and is formed with teeth 54^a which are also in mesh with the teeth of the 50 pinion 50, the width of the teeth of the pinion being sufficient to engage both the teeth on the shank of the awl and those on the rack bar. A block 56 is mounted on a pin secured in the end of the rack bar 54, and is 55 received in a recess or slot in the forward end of a lever 58 pivoted at 60 on the link 26 and connected by a link 62 with an arm 64 mounted on a rock shaft 66. In order to actuate the rock shaft 66 the arm 68 is secured thereto and carries a cam roll 70 which engages a cam groove 72 also formed in the cam disk 44. Through the connections described the oscillation of the arm 68 causes the reciprocation of the rack bar 54 65 in the awl bar which rotates the pinion 50

to project the awl into engagement with the work and to withdraw the awl from engagement with the work. The mechanism for projecting and withdrawing the awl with relation to the awl bar is actuated in timed 70 relation to the mechanism for imparting the lateral movements to the awl bar so that the awl is projected into engagement with the work while the awl bar is moved laterally to feed the work and the awl is withdrawn 75 from engagement with the work when the awl bar is brought back to its initial position ready to begin a work feeding stroke.

The connection between the link 62 and the arm 64 is arranged so that its center is 80 substantially in alignment with the axis of the rock shaft 30 and the pivotal connection between the link 62 and the lever 58 is arranged so that its center lies substantially in alignment with the center of the pivotal connection between the arm 28 and the link 26. when the awl is projected into engagement with the work as shown in Fig. 4. The result of this arrangement is that the movement of the feeding mechanism does not 85 affect the position of the lever 58 with relation to the link 24 during the work feeding movement of the feeding devices, and the position of the awl with relation to the awl bar is substantially unchanged while the 90 work is being fed.

Having explained the nature and object of the invention, and having specifically described a machine embodying the same in its preferred form, what is claimed is:—

1. A shoe sewing machine having, in combination, stitch forming devices including a straight hook needle, a rotatable horn, feeding means comprising a movable awl bar, an awl movably mounted in the bar, means for moving the awl bar laterally, and means for moving the awl with relation to the awl bar into and out of engagement with the work in timed relation to the lateral movements of the awl bar.

2. A shoe sewing machine having, in combination, stitch forming devices including a straight hook needle, a rotatable horn, feeding means comprising an awl bar, an awl movably mounted in the bar, means for moving the awl bar laterally, and mechanism for moving the awl with relation to the awl bar into and out of engagement with the work, comprising a rack bar upon which the awl is carried, slidably mounted in the awl bar, a pinion rotatably mounted in the awl bar and engaging the rack bar, a second rack bar slidably mounted in the awl bar and engaging the pinion, and means for reciprocating the second rack bar.

3. A shoe sewing machine having, in combination, stitch forming devices including a straight hook needle, a rotatable horn, a presser foot, feeding means comprising a laterally movable awl bar, a connection be-

tween the awl bar and the presser foot for raising and lowering the awl bar in accordance with changes in the position of the presser foot, an awl movably mounted in the awl bar, and means for advancing and retracting the awl with relation to the awl bar into and out of engagement with the work.

4. A shoe sewing machine having, in combination, stitch forming devices including a straight hook needle, a rotatable horn, feeding means comprising an awl bar, means for moving the awl laterally including an oscillatory lever and a link connecting the lever with the awl bar, an awl movably mounted in the awl bar, means for advancing and retracting the awl into and out of engagement with the work in timed relation to the lateral movements of the awl bar including a lever pivoted on the link, a connection between the lever and the awl, and means for swinging the lever about its pivotal connection with the link.

5. A shoe sewing machine having, in combination, stitch forming devices including a straight hook needle, a work support, a presser foot, a work feeding awl, an awl bar, a connection between the presser foot and the awl bar to vary the vertical position of the awl bar in accordance with variations in the vertical position of the presser foot due to changes in the thickness of the work, means for imparting lateral movements to the awl bar, and means for advancing and retracting the awl with relation to the awl bar.

6. A shoe sewing machine, having, in combination, stitch forming devices including a straight hook needle, a work support, a presser foot, a work feeding awl, a swinging awl bar, a connection between the presser foot and the awl bar to vary the vertical position of the awl bar in accordance with variations in the vertical position of the presser foot due to changes in the thickness of the work, means for imparting lateral swinging movements to the awl bar, and means for advancing and retracting the awl with relation to the awl bar.

7. A shoe sewing machine, having in combination, stitch forming devices including a

straight hook needle, a work support, a presser-foot, a work-feeding awl, a swinging awl bar, an awl movably mounted in the bar, means for swinging the awl bar laterally, and means for moving the awl with relation to the awl bar into and out of engagement with the work in timed relation to the swinging movements of the awl bar.

8. A shoe sewing machine, having in combination, stitch forming devices including a straight hook needle, feeding means comprising a movable awl bar, an awl movably mounted in the bar, means for moving the awl bar laterally comprising an oscillatory lever, an awl movably mounted in the awl bar, mechanism for advancing and retracting the awl with relation to the awl bar into and out of engagement with the work in timed relation to the lateral movements of the awl bar comprising a series of relatively movable parts, a connection between one of said parts and the awl bar, and a pivotal connection between certain of said parts arranged to be brought into alinement with the axis of the oscillatory lever when the awl is at the limit of its advancing movement.

9. A shoe sewing machine, having in combination, stitch forming devices including a straight hook needle, feeding means comprising an awl bar, means for moving the awl laterally including an oscillatory lever and a link connecting the lever with the awl bar, an awl movably mounted in the awl bar, means for advancing and retracting the awl with relation to the awl bar into and out of engagement with the work in timed relation to the lateral movements of the awl bar, including a second oscillatory lever, a lever pivoted on the link and a link having a pivotal connection at one end with the second oscillatory lever arranged to be brought into alinement with the axis of the first oscillatory lever, and a pivotal connection at its other end with the last lever arranged to be brought into alinement with the pivotal connection between the first oscillatory lever and the first link when the awl is at the limit of its advancing movement.

FRED ASHWORTH.
